UNITED STATES PATENT OFFICE

JOHN D. STUART, OF SOUTH EUCLID, OHIO

DESIGN FOR A LAMP GLOBE

Application filed November 16, 1931. Serial No. 41,742. Term of patent 3½ years.

To whom it may concern:

Be it known that I, JOHN D. STUART, a citizen of the United States, residing at South Euclid, in the county of Cuyahoga and State of Ohio, have invented a new, original, and ornamental Design for a Lamp Globe, of which the following is a specification, reference being had to the accompanying drawing, forming a part thereof.

In the drawing, Fig. 1 is a side elevation, and Fig. 2 is a plan view of my globe.

I claim:

The ornamental design for a lamp globe, substantially as shown.

JOHN D. STUART.
